CLAIM

The ornamental design for a tub for bathing, as shown and described.

DESCRIPTION

FIG. 1 is a left, top, front perspective view of a tub for bathing embodying my new design;

FIG. 2 is a top plan view thereof;

FIG. 3 is a front elevational view thereof;

FIG. 4 is a rear elevational view thereof;

FIG. 5 is a left side elevational view thereof, the right side elevational view being a mirror image of the left side shown;

FIG. 6 is a cross-sectional view taken along line 6—6 of FIG. 2; and,

FIG. 7 is a cross-sectional view taken along line 7—7 of FIG. 2.
